UNITED STATES PATENT OFFICE

BELA R. HALDERMAN, OF FRANKLIN GROVE, ILLINOIS.

DESIGN FOR A CIGAR-ASH HOLDER.

42,603.

Specification for Design.

Patented June 11, 1912.

Application filed January 13, 1912. Serial No. 671,131. Term of patent 7 years.

To all whom it may concern:

Be it known that I, BELA R. HALDERMAN, a citizen of the United States, residing at Franklin Grove, in the county of Lee and State of Illinois, have invented a new, original, and ornamental Design for Cigar-Ash Holders, of which the following is a specification, reference being had to the accompanying drawing, forming part thereof.

The figure is a perspective view of a cigar ash holder, showing my new design.

I claim:

The ornamental design for cigar ash holder, as shown.

BELA R. HALDERMAN.

Witnesses:

M. V. PETERMAN,

M. Z. PHILLIPS.
